SPEED REDUCER HOUSING OR SIMILAR
ARTICLE

Edward J. Wellauer, Wauwatosa, and Raymond F. Pickel,
West Allis, Wis., assignors to The Falk Corporation,
Milwaukee, Wis., a corporation of Wisconsin

Filed Apr. 1, 1963, Ser. No. 74,224

Term of patent 14 years

(Cl. D55—1)

FIG. 1

FIG. 2

FIG. 3

FIG. 1 is a view in perspective of a speed reducer housing showing our new design;

FIG. 2 is a top plan view of the same; and

FIG. 3 is a view in perspective of the housing taken from a diametrically opposed position from the view of FIG. 1.

The dominant features of the design reside in the portions shown in full lines.

We claim:

The ornamental design for a speed reducer housing or similar article, as shown and described.
